UNITED STATES PATENT OFFICE.

LOUIS S. EMERY, OF INDIANAPOLIS, INDIANA, AND JAMES J. MAGINN, OF LIMA, OHIO.

FEED-WATER PURIFIER FOR LOCOMOTIVES.

Application filed August 7, 1922. Serial No. 580,253.

Our said invention relates to a feed water purifier intended primarily for use in locomotives though it is applicable also to other boilers as for example the boilers of stationary engines. It is an object of our invention to provide feed water purifying means on the inside of the boiler with means also inside the boiler for injecting feed water into the purifying device.

10 A further object of the invention is to provide an inside water circulation whereby the hot water from the boiler becomes mingled with the injected cold water without leaving the confines of the boiler and 15 thus being lowered in temperature.

Referring to the accompanying drawings, which are made a part hereof and on which similar reference characters indicate similar parts,

20 Figure 1 is a transverse section of the boiler on line 1—1 of Figure 2,

Figure 2 a longitudinal section on line 2—2 of Figure 1, and

25 Figure 3 a section on line 3—3 of Figure 2.

In the drawings reference character 10 indicates the outer shell of a boiler containing tubes 11.

Underneath the boiler is a sludge drum 30 12 having a bottom piece 13 with a depending portion threaded at one end at 14 to receive a blow-off cock (not shown) by means of which the sediment may be removed from the drum. Openings 15 lead 35 from the boiler into the drum and an annular baffle 16 separates these openings from a central opening 17 leading back to the boiler.

Bowed strips of sheet metal 18 are 40 secured to the sides of the boiler as by rivets 19 and form with the boiler wall precipitation pipes located internally of the boiler. Feed water pipes 20 extend through the wall of the boiler into the precipitation pipes 18. 45 An opening 21 adjacent to the top of the sludge drum serves for attachment of a pipe for purposes of cleaning and is normally closed by a cock. The cock in this pipe may be operated by a handle accessible from the 50 running board, as in the application of Everett 374,389, filed April 16, 1920.

In the operation of our device cold water is introduced into a precipitation pipe 18 through a feed water pipe 20 and meets immediately with a stream of water at boiler 55 temperature passing down in the precipita-

tion pipe. It will be noted that the feed water pipes are turned down to force the stream of entering water downward in the precipitation pipes. Because the temperature of the hot water has not been reduced by leading it out of the boiler, the cold water will immediately be mingled with very hot water. Furthermore as the mixture travels slowly downward in the precipitation pipe 60 it is still subjected at three sides to boiler temperature thereby heating the incoming water to a much higher temperature than would otherwise be the case and lessening its specific gravity and density and so causing a very complete precipitation of the solid matter carried thereby before it rises into the boiler. Such solid matter is precipitated in the pipes 18 and carried down into the sludge drum by the currents of water 65 and deposited in the sludge drum while the water passes down to the lower end of the baffle 16 and then up through the opening 70 17 into the boiler.

Having thus fully described our said invention, what we claim as new and desire to secure by Letters Patent, is:

1. A boiler feedwater purifier comprising a sludge drum attached to said boiler and communicating therewith, a baffle pipe surrounding the opening from the sludge drum into said boiler and extending for a distance into said sludge drum, a pipe within said boiler communicating at its lower end with said sludge drum outside the baffle pipe and 80 at its upper end with the interior of the boiler, and a feed-water pipe arranged to discharge into said first-mentioned pipe near the upper end thereof, substantially as set forth.

2. A feed water purifier adapted for use in a boiler having circulating currents and comprising an upright submerged heat conducting tube located in the boiler adjacent a downward current and having its upper end open to receive a fraction of said downward current, a connection near its upper end to admit boiler feed water, a sludge drum joined to the lower end of the tube and having an outlet to return the fractional intake of the tube along with the admitted feed water back to the general circulation of the boiler, substantially as set forth.

3. A feed water purifier for boilers comprising a sludge drum attached to the lower side of the boiler, a baffle concentric therewith depending from the bottom of the

boiler, upright precipitation pipes extending along opposite side walls of the boiler leading into the sludge drum and being wholly within the boiler, and feed water pipes extending through the walls of the boiler into the precipitation pipes the latter pipes being open at the top, substantially as set forth.

4. A feed water purifier for use in a boiler having circulation currents comprising a sludge drum attached to the underside of the boiler with an outlet into the boiler, a bowed strip of sheet metal within the boiler and secured to the wall thereof to form a precipitation pipe with an outlet into the sludge drum, means for injecting feed water into said precipitation pipe, said pipe being open at the top and submerged, whereby part of the circulation of boiler water is diverted

through the purifying system, substantially as set forth.

5. The combination of a boiler having a pair of spaced holes in its bottom, a downwardly extending flange about one of said holes, a precipitation pipe leading from a point adjacent the water level to the other hole, a feed pipe near the upper end of said precipitation pipe, and a sludge drum surrounding said flange and both of said holes in the bottom of the boiler, substantially as set forth.

In witness whereof, we have hereunto set our hands at Indianapolis, Indiana, this 28th day of July, A. D. nineteen hundred and twenty-two.

LOUIS S. EMERY.
JAMES J. MAGINN.
